(57) **CLAIM**

The ornamental design for a baby carrier hipseat, as shown and described.

DESCRIPTION

FIG. 1 is a perspective view of a baby carrier hipseat showing the claimed design;
 FIG. 2 is another perspective view thereof;
 FIG. 3 is a front elevational view thereof;
 FIG. 4 is a rear elevational view thereof;
 FIG. 5 is a left side view thereof;
 FIG. 6 is a right side view thereof;
 FIG. 7 is a top plan view thereof;
 FIG. 8 is a bottom plan view thereof;
 FIG. 9 is a partial enlarged view of FIG. 1 thereof; and,
 FIG. 10 is another partial enlarged view of FIG. 1 thereof. The broken lines depict portions of the baby carrier hipseat that form no part of the claimed design.
